(57) **CLAIM**

Ornamental designs for a battery operated oil hydraulic crimping tool and a middle portion of the same.

DESCRIPTION

FIG. 1 is a front elevation view of a middle portion of the battery operated oil hydraulic crimping tool,

FIG. 2 is a rear elevation view thereof,

FIG. 3 is a top plan view thereof,

FIG. 4 is a bottom plan view thereof,

FIG. 5 is a left elevation view thereof,

FIG. 6 is a right elevation view thereof,

FIG. 7 is a right elevation view of the middle portion of the battery operated oil hydraulic crimping tool when the battery operated oil hydraulic crimping tool is cut along A-A line in FIG. 1; and,

FIG. 8 is a perspective view thereof.

The broken line showing of the battery operated oil hydraulic crimping tool is included for the purpose of illustrating environmental structure and forms no part of the claimed design. The A arrows is included in FIG. 1 for the purpose of illustrating how the battery operated oil hydraulic crimping tool is seen in FIG. 7 and forms no part of the claimed design.

The battery operated oil hydraulic crimping tool is equipped with a rechargeable battery and used to hold and crimp a crimping terminal or sleeve with four dies coming close to one another with three of them stuck out inward on oil hydraulic pressure.
